UNITED STATES PATENT OFFICE.

LAWRENCE J. JOHNSON, OF KANSAS CITY, MISSOURI.

SHOW-CASE.

SPECIFICATION forming part of Letters Patent No. 692,670, dated February 4, 1902.

Application filed January 19, 1901. Serial No. 43,911. (No model.)

To all whom it may concern:

Be it known that I, LAWRENCE J. JOHNSON, a citizen of the United States, and a resident of Kansas City, Jackson county, Missouri, have invented a new and useful Show-Case, of which the following is a specification.

My invention relates to improvements in show-cases, and has for its object to improve the construction and appearance of the same in a manner that will hereinafter appear.

In show-cases as generally constructed the glass plates are held in place at the corner-posts by strips or stops, which are tacked in place from the inside of the case after the glass has been put in place. This construction primarily lacks rigidity and firmness--prerequisites of a good case. Moreover, it is impossible to fit these strips or stops accurately enough to entirely exclude dust. Therefore the case must be constantly cleaned in order to keep the case in a presentable appearance. The amount of wood used in these cases not only makes a clumsy appearance, but the manner in which the wood is employed allows the same to work loose from constantly opening and closing the doors, as well as other causes. Another method of making show-cases is to discard the wooden corner-posts entirely and rely upon either metallic corner-clasps or upon cementing the glass corners together. The type of case in which the clasps are used is not only very expensive to produce, but is subject to damage or destruction by settling of the floors or other foundation upon which it rests, as all the strain is centered upon the glass in the immediate vicinity of the clasps. Cases made by cementing the corners of the glass together and eliminating the wood entirely are very unreliable, as the joints invariably loosen or break the glass under the influence of the atmosphere or other causes. Moreover, these cases offer a very cold and uninviting appearance, thus detracting very much from their value. By my invention these disadvantages are overcome entirely, while the cost of production is much decreased from that of the all-glass case. Cases constructed in accordance with my invention contain just enough wood to form a solid structure and to make a neat and pleasing appearance, and this

wood is employed to the best possible advantage, as will hereinafter appear.

In order to more fully explain my said invention, reference will be had to the accompanying drawings, in which—

Figure 1 represents a perspective view of the completed case. Fig. 2 is a central horizontal section of the same. Fig. 3 is a central vertical section of the case looking toward the rear. Fig. 4 is an enlarged detail sectional view taken on the line IV IV, Fig. 5. Fig. 5 is a similar view taken on the line V V, Fig. 4; and Fig. 6 is a broken sectional view taken upon the line IV, Fig. 2.

1 designates a base-frame which runs completely around the case beneath the glass. The rear surface of this base-frame 1 is provided with a pair of parallel longitudinal grooves 2 2, in which run the ball-bearings 7 8, supporting the sliding doors 16.

3 represents a molding or cornice secured to the base-frame 1, and 4 designates the base proper, which may be either integral or otherwise.

Into the base-frame 1 at the four corners thereof are secured dowel-pins 5, projecting upwardly in the recess 6 of the round corner-post 7. This corner-post in an ordinary-sized case is preferably not over one-half an inch 80 in diameter. The rear corner posts or standards 8 are preferably rectangular in cross-section to accommodate the width of the two sliding doors. Upon the top of these four corner-posts 7 8 is placed a narrow rectangular strip 9 and is suitably fastened upon the tops of the four corner-posts when the glass is in position. Upon the upper side of this frame 9 is cemented a heavy strip of felt 10 or the like, which is in turn cemented to the 90 glass top plate 11. This felt strip is preferably formed of such material and nature that should it be desired to remove the top plate it is simply necessary to insert a knife-blade or the like in the middle of the strip and separate it into two halves. In replacing the top plate the two halves of the felt strip are removed from the frame 9 and plate 11, respectively, and a new one substituted therefor.

12 represents the front glass plate of the 100 case, and 13 the two end plates. These plates are secured in position in the following man-

ner: The corner-posts 7 and 8 are provided with vertical grooves 14 14, extending from top to bottom of the same. These grooves are of such a width as to form a tight sliding fit with the glass plates 12 and 13. These glass plates 12 and 13 are inserted in place from the top, while the top plate 11 and frame 9 are removed by sliding the same into place from the top of the grooves and not from the inside of the case, as heretofore. If desired, these grooves 14 may be provided with any suitable cement to form a solid joint; but ordinarily this will be unnecessary. This method of inserting the glass in the case is a very important feature. Should it become necessary to replace a glass for any reason, it will not be necessary to remove the contents of the case, as is now required; but the plate and frame 11 and 9, respectively, are removed and the new glass slid into place from the top, as hereinbefore described. These plates 12 and 13 are preferably set into grooves 15 in the top frame 9 and base-frame 1, as shown.

16 16 represent sliding doors upon the rear of the case, composed almost entirely of glass, as shown, just enough wood being used as is consistent with strength. The upper ends of these doors are narrowed, as shown, and partially fill the grooves 17, as shown. To remove the doors, the same are raised and the bottom swung outward from the grooves 2.

20 represents a marble or other suitable foundation upon which the case may be mounted.

35 Thus it will be observed that a case is produced wherein just enough wood is employed to insure strength and rigidity and to make a stylish, finished, and attractive appearance without the use of clamps, screws, or stops to 40 secure the glass in position.

While I have shown my invention as applied to a rectangular case, it is to be understood that I do not limit myself to such a type of case, as the same may be round or of any desired shape. It is also obvious that many modifications will suggest themselves to any one skilled in the art to which my invention appertains.

Having thus described my invention, what 50 I claim, and desire to secure by Letters Patent of the United States, is—

1. In a show-case, the combination with a base-frame, provided with grooves, posts or standards provided with radial grooves throughout their length, dowel-pins securing 55 said posts to said frame, glass plates adapted to be slid into said grooves from their upper ends, a grooved top frame, adapted to be secured upon the top of said posts, and into which said glass plates fit, a felt strip cemented upon the upper side of said top frame, and a glass top plate cemented upon said strip, substantially as described.

2. In a show-case, the combination with a base-frame, posts or standards supported 65 thereby, glass side plates inserted between said posts, and a frame supported upon the tops of said posts; of a felt strip cemented upon the upper side of said frame, and a glass top plate laid upon and cemented to said felt 70 strip, substantially as described.

3. In a show-case, the combination with a base-frame, corner posts or standards supported upon said frame, glass side plates adapted to fit in grooves in said posts, and a frame 75 secured upon the tops of said posts, and grooved upon its under side to receive the tops of said side plates; of a felt strip cemented to the upper side of said frame, and a glass top plate cemented to the top of said felt strip, sub- 80 stantially as described.

4. In a show-case, the combination with a base-frame, corner posts or standards supported upon said frame, glass side plates adapted to slide in grooves in said posts, and a rectangular frame secured upon the tops of said 85 posts encircling the top of the case, and provided upon its under side with grooves adapted to receive the tops of said side plates; of a heavy felt strip cemented to the upper side 90 of said frame, and a glass top plate cemented upon the top of said felt strip, in such manner that said top plate may be removed by the insertion of a knife-blade or the like through said felt to separate said felt into two strips, 95 substantially as described.

In testimony whereof I affix my signature in the presence of two witnesses.

LAWRENCE J. JOHNSON.
